UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

ROCK DRILL.

Application filed November 18, 1926. Serial No. 149,128.

This invention relates to rock drills, but more particularly to a spring pressed valve block forming a seat for the distributing valve of fluid actuated rock drills of the hammer type.

The objects of the invention are to secure the valve block in operative position in an improved and simplified manner and to reduce the cost of manufacturing the constituent parts of the valve chest.

Other objects will be in part obvious and in part pointed out hereinafter.

The invention consists of the combination of elements and arrangement of parts substantially as hereinafter described and claimed and illustrated in the accompanying drawings, in which

Figure 1 is a sectional elevation of so much of a rock drill as will serve to illustrate the invention,

Figure 2 is a sectional elevation taken through Figure 1 on the line 2—2 looking in the direction of the arrows, and

Figure 3 is a plan view partly in section taken through Figure 2 on the line 3—3 looking in the direction of the arrows.

Referring to the drawings, the invention is shown embodied in a rock drill having a cylinder A, only the rearward portion of which is shown for illustrative purposes. Front and rearward inlet passages B and C respectively are formed in the cylinder to deliver pressure fluid to the end of the cylinder for impelling the hammer piston D disposed within a piston chamber E.

At the rearward end of the piston chamber E and forming a continuation thereof is an enlarged bore F. In the front end of said bore is disposed a back cylinder washer G which forms a closure for the rearward end of the piston chamber E. A rifle bar H extends through an aperture J of the back cylinder washer G and engages the piston D in the usual manner for rotating the working implement (not shown) against which the hammer piston delivers its blow. The rifle bar H is provided with the usual head K which carries spring pressed pawl members L adapted to engage a toothed ratchet ring O which encircles the head K and is seated on the rearward face of the back cylinder washer G.

A valve block P disposed in the rearward end of the bore F is seated on the ratchet ring O and the head K of the rifle bar H

and has a pair of supply passages Q and R which lead from a seating surface S of the valve block P to register with the front and rearward inlet passages B and C respectively. The valve block P and rotation 60 ratchet O and the back cylinder washer G are in this instance held against rotation in the bore F by a key or pin T disposed in slots U formed in the members intended to be keyed together.

Disposed at the rearward end of the cylinder A is a back head V preferably clamped to the cylinder by side bolts W and is provided on its inner face with an annular flange X which extends into the bore F. The flange X is preferably only of sufficient length to centralize the back head with respect to the cylinder. A connection Y leading from a suitable source of pressure fluid supply is connected to the back head V and communicates with an annular recess Z in the inner face of the back head through a passage b for delivering pressure fluid to a valve chamber c formed by the valve block P and the back head V.

The distribution of such pressure fluid to the ends of the cylinder is in this instance controlled by an oscillatory plate valve d seated on the seating surface S. The valve d may be pivoted in the chamber c in any suitable manner. In the present instance this is accomplished by means of a sleeve e through which extends a water tube V'. The sleeve e is preferably seated at one end in the back head V and at its other end in the valve block P.

In drills of the type to which the present invention is applied, it has heretofore been customary to form the flange X of a length to permit its inner face to abut the valve block P for the purpose of clamping said valve block in operative position. Such construction, however, has been found to be expensive for the reason that considerable time and skill is required in properly machining the cooperative surfaces of the back head and the valve block. The present invention aims to simplify the construction of these elements and consequently to reduce the cost of manufacturing the same. To this end the inner face of the back head V is provided with forwardly extending ribs f suitably spaced to form a slot g therebetween for the reception of a plate spring h having in this instance an arcuate intermediate portion j 110

which bears against the roof of the slot *g*. At the ends of the spring are formed reversely curved portions *h* which press against the seating surface *S* to hold the 5 valve block *P* and, in the construction shown, the ratchet ring *O* and the back cylinder washer *G* against longitudinal movement in the bore *F* in a rearwardly direction. In the 10 present instance the spring *h* has a central aperture *o* through which the sleeve *e* extends for preventing endwise movement of the spring.

By means of the present invention a considerable saving is effected in the cost of 15 the construction and operation of rock drills of the type to which the present invention may be applied. This construction eliminates the necessity of machining the parts disposed in the bore *F* to accurate fits and enables such 20 parts to be readily removed from the bore *F* for the purposes of inspection and replacement of parts.

I claim:

1. In a fluid actuated rock drill the combination of a cylinder having a piston chamber with an enlarged bore at one end, a valve block in the bore, a back head for the cylinder cooperating with the valve block to form a valve chamber, means extending 25 through the valve chamber for conveying cleansing fluid through the drill, and a spring in the valve chamber encircling the said means pressing against the back head and the valve block to hold said valve block 30 immovable in the bore.

2. In a fluid actuated rock drill, the combination of a cylinder having a piston chamber with an enlarged bore at one end, a valve block in the bore having a seating surface, a back head for the cylinder cooperating 40 with the valve block to form a valve chamber, a valve in the valve chamber resting on the seating surface, and a spring spanning the valve and in engagement with the seating surface and the back head to hold the said valve block against longitudinal 45 movement with respect to the cylinder.

3. In a fluid actuated rock drill, the combination of a cylinder having a piston chamber with an enlarged bore at one end, a valve block in the bore, a back head for the cylinder cooperating with the valve block to form a valve chamber, an oscillatory plate valve 50 in the valve chamber, and a plate spring spanning the valve and in engagement with the back head and the valve block to hold the valve block immovable in the bore.

4. In a fluid actuated rock drill, the combination of a cylinder having a piston chamber with an enlarged bore at one end, a valve 60

block in the bore, a back head for the cylinder cooperating with the valve block to form a valve chamber, means in the bore forming a seat for the valve block and a spring in the valve chamber pressing against the back head and the valve block for holding the valve block and said means against longitudinal movement with respect to the cylinder. 65

5. In a fluid actuated rock drill, the combination of a cylinder having a piston chamber with an enlarged bore at one end, a valve block in the bore, a back head for the cylinder cooperating with the valve block to form a valve chamber, an oscillatory plate valve in the valve chamber, and an arcuate plate spring in the chamber disposed at right angles to the valve, the intermediate arcuate portion of the spring being seated on the back head and the ends of the spring on the valve block for holding 70 said valve block in operative position. 75

6. In a fluid actuated rock drill, the combination of a cylinder having a piston chamber with an enlarged bore at one end, a valve block in the bore, a back head for the cylinder cooperating with the valve block to form a valve chamber, an oscillatory plate valve in the valve chamber, and a spring in the chamber spanning the valve at right angles thereto, said spring comprising an intermediate curved portion seated on the back head and reversely curved end portions seated on the valve block to hold the valve block 80 securely in assembled position. 85

7. In a fluid actuated rock drill the combination of a cylinder having a piston chamber with an enlarged bore at one end, a back head for the cylinder having a slot across its inner end face, a valve block in the bore cooperating with the back head to form a valve chamber, an oscillatory plate valve in the valve chamber, and a plate spring spanning the valve at right angles thereto, said spring comprising an intermediate curved portion seated in the slot and reversely curved end portions bearing on the valve block to hold the valve block immovable in the bore. 90 95

8. In a fluid actuated rock drill, the combination of a cylinder having a bore, a valve block in the bore, a back head on the cylinder cooperating with the valve block to form a valve chamber, and a spring in the valve chamber exerting a pressure on the valve block for holding said valve block immovable in the bore. 100 105 110

In testimony whereof I have signed this specification.

FRED M. SLATER.
